EMANUEL PALMIERI, OF NEW YORK, N. Y.

PUSH BUTTON VALVE

Application filed April 12, 1932. Serial No. 604,787.

The invention relates to a push button valve and more especially to a push button control for water supply systems in bathrooms, kitchens or other places.

5 The primary object of the invention is the provision of a device of this character, wherein for example, water to be supplied to a bathtub, basin or other fixture, can be conveniently controlled through the use of a

10 push button, thereby eliminating the conventional use of faucets or the like with the turn valves or other forms of hand controlled valves, the device being novel in form and is readily and conveniently operable so that

15 water supply will be controlled for the admission of water or the cutting off thereof at will.

Another object of the invention is the provision of a device of this character, wherein the same is susceptible of mounting in the 20 wall of a room and will control a fluid supply as the supply will be regulated under the use of push buttons, these being manually depressed for the opening or closing of the control for the fluid supply, the valve for the 25 supply and the mounting of the device being novel in their structural make-up.

A further object of the invention is the provision of a device of this character which is extremely simple in construction, effective as a single control, thoroughly reliable and efficient in its purpose, durable, and inexpensive in manufacture and installation.

With these and other objects in view, the invention consists in the features of construction, combination and arrangement of parts as will be hereinafter more fully described in detail, illustrated in the accompanying drawings, which disclose the preferred embodiment of the invention, and 40 pointed out in the claims hereunto appended.

In the accompanying drawings:

Figure 1 is a fragmentary elevation partly diagrammatically shown of a bathtub 45 with the water supply system and the push button device constructed in accordance with the invention in association.

Figure 2 is an enlarged plan view of the push button device.

50 Figure 3 is an enlarged sectional view tak-

en on the line 3-3 of Figure 2 looking in the direction of the arrows.

Figure 4 is an elevation partly broken away.

Figure 5 is a sectional view of the deflector at the bottom of the tub.

Similar reference characters indicate corresponding parts throughout the several views in the drawings.

Referring to the drawings in detail, A 60 designates generally a bathtub which is of conventional type having a water inlet lead B communicative with the tub A through its bottom and this lead B through the branches 10 and 11 is common to the hot and cold water conduits or pipes 12 and 13 respectively, while above the tub is arranged a shower equipment 14 having the pipe 15 leading thereto from the branches 16 and 17 respectively from the pipes 12 and 13. Intersecting the branches 10 and 11 and 15 and 16, each, is a valve casing including the sections 18 and 19 respectively, these being interfitted and threaded together. The section 18 is 65 formed with an internal valve seat 20 normally engaged by a valve 21 which is held seated under the tension of a spring 22 held in place by the section 19 which is formed internally thereof with an anchoring shoulder 23 for the spring 22.

70 Suitably built into the wall 24 of an enclosure constituting the bathroom is a frame 25 having a face plate 26 and this frame supports a coupling plate 27 for nipples 28 on the sections 18 of the valve casings. The nipples 28 are held with the coupling plate 27 by set screws 29'. The nipples 28 each is formed with a packing gland 30 through which works the stem 31 of a push button 32, 75 the latter being projected through a suitable opening therefore in the face plate 26. In this instance there is provided a series of four push buttons, one for the branch 10, another for the branch 11, another for the branch 16 and another for the branch 17 as will be clearly apparent in Figure 2 of the drawings. Each stem 31 is formed with a series of spaced ratchet rings or shoulders 33 for successive engagement of a sliding dog 34 fitted 80 in guides 35 upon a shiftable plate 36. Each 85

dog 34 is tensioned by a spring 37 mounted between ears 38 on the dog 34 and ears 39 on the plate 36 respectively, the spring 37 yieldably urging the dog 34 in latching relation to the rings or shoulders 33 as will be clearly apparent from Figures 3 and 4 of the drawings.

The shiftable plate 36 is mounted in guides 40 on the coupling plate 27 and is tensioned by springs 41 connected therewith and with said plate 27. The plate 36 is formed with a top ledge 42 which normally rests upon the uppermost guides 40 and constitutes a stop for limiting the downward movement of said plate 36 in the frame 25.

Arranged in the frame 25 between the face plate 26 and the coupling plate 27 is a shiftable yoke 43 provided centrally thereof with a push button 44, the latter protruded through a suitable opening to without the face plate 26 and this yoke is provided with lifter cams 45, these engageable with the shiftable plate 36, the yoke 43 being tensioned by springs 46 connected thereto and to the face plate 26 so that the yoke is normally drawn in a direction to have the lifter cams 45 retracted from the plate 36. Upon depressing the button 44 the lifter cams 45 will act upon the plate 36 to lift the same and in this movement the dogs 34 will be simultaneously released from the shoulders or rings 33 on the stems 31 of the buttons 32. The buttons 32 upon release will assume normal position under the action of the springs 22 upon the valves 21 and these springs also will cause the closing of said valves. On depressing each of the buttons 32 the valve 21 controlled thereby will be opened and the stem 31 of said button 32 will be latched by the dog 34 engaging in one of the shoulders or rings 33, these shoulders or rings determining the opening extent of the valves 21 under depression of the buttons 32. As has been stated, to release the buttons 32 depressed the button 44 is depressed so that the lifter cams 45 will lift the plate 36 and the buttons 32 be instantly released for the automatic closing of the valves 21. In this manner of operation of the valves 21 the water supply to the lead B and to the lead 15 will be controlled, either full supply had, or complete cutting off thereof.

The lead B communicating with the tub A at its bottom has fitted therein a deflector cap 47 supported upon a bolt 48 held in a spider 49 and this cap functions to break up the stream of water under pressure from the lead B because otherwise the stream would rise above the top of the tub and thus the water will be deflected about the bottom of said tub A without any possibility of an elevation of the stream so that in this manner the tub will be filled with water and the drain therefrom is had through the discharge pipe 50 leading from the bottom of the tub.

It should be apparent that the push but-

ton control as hereinbefore described is applicable for the regulation of fluid supply other than water, although such control is designed primarily for use with water fixtures, such as bathtubs, washbowls, sinks or the like.

There is a single button 32 for the hot water supply and for the cold water supply, while a single button is for the release of the before mentioned buttons.

What is claimed is:—

1. The combination with a fluid supply lead, of a valve within said lead and normally closed, a push button active upon the valve to open the same, means for regulating the extent of opening movement of said valve, and a push button operated means for releasing the first named push button when depressed.

2. The combination with a fluid supply lead, of a valve within said lead and normally closed, a push button active upon the valve to open the same, means for regulating the extent of opening movement of said valve, a push button operated means for releasing the first named push button when depressed, and a wall mounting for said push buttons.

3. The combination with a fluid supply lead, of a valve within said lead and normally closed, a push button active upon the valve to open the same, means for regulating the extent of opening movement of said valve, a push button operated means for releasing the first named push button when depressed, a wall mounting for said push buttons, and means coacting with the valve for tensioning the same in a seating direction.

4. The combination with a fluid supply lead, of a valve within said lead and normally closed, a push button active upon the valve to open the same, means for regulating the extent of opening movement of said valve, a push button operated means for releasing the first named push button when depressed, a wall mounting for said push buttons, means coacting with the valve for tensioning the same in a seating direction, and a deflector for the discharge end of said lead.

5. The combination with a fluid supply lead, of a valve within said lead and normally closed, a push button active upon the valve to open the same, means for regulating the extent of opening movement of said valve, a push button operated means for releasing the first named push button when depressed, a wall mounting for said push buttons, means coacting with the valve for tensioning the same in a seating direction, a deflector for the discharge end of said lead, and means for detachably coupling the wall mounting with the lead.

6. The combination with a fluid supply lead, of a valve within said lead and normally closed, a push button active upon the valve to open the same, means for regulating the

extent of opening movement of said valve, a push button operated means for releasing the first named push button when depressed, a wall mounting for said push buttons, means coacting with the valve for tensioning the same in a seating direction, a deflector for the discharge end of said lead, and means for detachably coupling the wall mounting with the lead, said lead comprising a sectional cas-
10 ing for the valve and tensioning means.

7. The combination with a fluid supply lead, of a valve within said lead and normally closed, a push button active upon the valve to open the same, means for regulating the extent of opening movement of said valve, a push button operated means for releasing the first named push button when depressed, a wall mounting for said push buttons, means coacting with the valve for tensioning the same in a seating direction, a deflector for the discharge end of said lead, means for detachably coupling the wall mounting with the lead, said lead comprising a sectional cas-
15 ing for the valve and tensioning means, one part of the casing being formed with a valve seat for said valve.

8. The combination with a fluid supply lead, of a valve within said lead and normally closed, a push button active upon the valve to open the same, means for regulating the extent of opening movement of said valve, a push button operated means for releasing the first named push button when depressed, a wall mounting for said push buttons, means coacting with the valve for tensioning the same in a seating direction, a deflector for the discharge end of said lead, means for detachably coupling the wall mounting with the lead, said lead comprising a sectional casing for the valve and tensioning means, one part of the casing being formed with a valve seat for said valve, and means for joining the deflector with the discharge end of said lead.

45 In testimony whereof I affix my signature.
EMANUEL PALMIERI.
